UNITED STATES PATENT OFFICE.

CHARLES EDWARD HAVILAND, OF LIMOGES, FRANCE.

DESIGN FOR A TEAPOT, &c.

SPECIFICATION forming part of Design No. 23,956, dated January 22, 1895.

Application filed December 13, 1894. Serial No. 531,733. Term of patent 7 years.

To all whom it may concern:

Be it known that I, CHARLES EDWARD HAVILAND, a citizen of the United States, residing at the city of Limoges, in the Republic of France, have invented and produced a new and original Design for a Teapot and Similar Articles, of which the following is a specification, reference being had to the accompanying drawings, forming part thereof, and in

10 which—

Figure 1 is a side elevation of a tea-pot bearing and incorporating my design, and Fig. 2 is a transverse section of same on the dotted line 2—2 of Fig. 1.

15 The leading feature of my design consists in the new and original shape and outline of the body of the tea-pot, as shown in the drawings forming a part of this application.

In the drawings A designates the body of

20 the tea-pot, which body inclines from its up-

per edge downward and outward on ornate lines as shown, and is composed of the vertical scalloped sections B. The upper and lower edges of the body A have ornamental scrolls C, D.

25 E designates the handle for the tea-pot, and F the pouring spout for the same.

Upon the tea-pot is a cover I having a handle J.

What I claim is—

30 The design for a tea-pot or similar article, substantially as shown and described.

Signed at the city of Limoges, in the Republic of France, this 23d day of November, A. D. 1894.

CHARLES EDWARD HAVILAND.
